US00D806691S

(12) **United States Design Patent** (10) **Patent No.:** **US D806,691 S**
(45) **Date of Patent:** **** Jan. 2, 2018**

(54) **COMMUNICATIONS EQUIPMENT**

(71) **Applicant:** **HMS Industrial Networks AB,**
Halmstad (SE)

(72) **Inventor:** **Rickard Andersson**, Haverdal (SE)

(73) **Assignee:** **HMS INDUSTRIAL NETWORKS**
AB (SE)

(**) **Term:** **15 Years**

(21) **Appl. No.:** **29/565,595**

(22) **Filed:** **May 23, 2016**

(30) **Foreign Application Priority Data**

Nov. 23, 2015 (EM) 002873497-0001

(51) **LOC (11) Cl.** **14-03**

(52) **U.S. Cl.**

(57) **CLAIM**

The ornamental design for communications equipment, as
shown and described.

DESCRIPTION

FIG. 1 is a first perspective view of a first embodiment of
communications equipment embodying my new design;
FIG. 2 is a second perspective view of the communications
equipment of FIG. 1;

FIG. 3 is a first side view of the communications equipment
of FIG. 1;

FIG. 4 is a second side view of the communications equipment
of FIG. 1;

FIG. 5 is a third side view of the communications equipment
of FIG. 1;

FIG. 6 is a fourth side view of the communications equipment
of FIG. 1; and,

FIG. 7 is a top view of the communications equipment of
FIG. 1.

1 Claim, 7 Drawing Sheets
